DECELERATING DEVICE FOR FIREARMS WITH TELESCOPIC BOLTS

Frederick P. Reed, Ludlow, Mass., assignor to the United States of America as represented by the Secretary of the Army

Filed Mar. 4, 1959, Ser. No. 797,317

1 Claim. (Cl. 89—185)

(Granted under Title 35, U.S. Code (1952), sec. 266)

The invention described herein may be manufactured and used by or for the Government for governmental purposes without the payment of any royalty thereon.

This invention relates to firearms provided with telescopic bolts and more particularly to a device for decelerating such bolts when going into battery position.

With those firearms of semiautomatic type wherein the bolt mechanism is cyclically actuated through forces produced by the discharge of a cartridge in the barrel, it has been discovered that the accuracy of a firearm of such type is adversely affected by the impact blow of the bolt with the barrel when the bolt is stopped thereagainst in battery position. The reasons for this inaccuracy are that the shock of impact sets up vibrations in the barrel which affects the courses of the projectiles when leaving the muzzle thereof and that the shock of inertia variably shifts the propellant and/or the projectiles in the cartridges to produce irregular flight characteristics.

In those firearms using single-piece bolts, the means for locking the bolt in battery position often times serve also to decelerate the bolts. But in the past there has not been provided any adequate means for decelerating those bolts of telescopic type wherein the bolt is stopped in battery position by the engagement thereof with the barrel and then is rotated to lock position by movement of a carrier relative to the bolt and no means have heretofore been provided for replacing the engaging surfaces which are worn or mutilated by the deceleration without having to replace major components as the bolt, barrel or receiver.

It is, therefore, an object of this invention to provide means for decelerating telescopic-type bolts when going into battery position.

It is another object of this invention to provide in the barrel assembly of a firearm having a telescopic-type bolt a replaceable decelerator member which is engageable by the bolt when going into battery position for gradually decelerating the bolt by uniformly converting the longitudinal movement thereof to a decelerated helical movement into battery position.

It is still another object of this invention to provide for firearms provided with bolts of stated type which have bayonet lugs disposed for rotating engagement with cooperating bayonet lugs in the barrel assembly a decelerator member separably mounted in the barrel assembly relative to the bayonet lugs therein for uniformly converting the longitudinal movement of the bolt to helical movement and the helical movement to rotary movement for a gradual deceleration of the bolt.

It is a further object of this invention to provide a decelerator which may be fabricated from material different from that of the bolt and barrel so that the deformative forces produced by the impact and engagement between the bolt and barrel assembly will be borne by such decelerator whereby defective engaging relationship between the bolt and barrel during deceleration may be easily repaired by replacing the decelerator and thereby

2

save having to replace the more expensive barrel or bolt.

The specific nature of the invention as well as other objects and advantages thereof will clearly appear from a description of a preferred embodiment as shown in the accompanying drawings in which:

Fig. 1 is a longitudinally cross-sectioned side view of a firearm receiver showing the bolt in locked extended position and clear of the barrel assembly;

10 Fig. 2 is a view similar to Fig. 1 but showing the bolt in locked battery position;

Fig. 3 is a partially cross-sectioned top view of the receiver showing the position of the bolt at moment of impact with the decelerator;

15 Fig. 4 is a view similar to Fig. 3 but showing the bolt helically actuated by the decelerator to battery position;

Fig. 5 is a view along line 5—5 of Fig. 1;

Fig. 6 is a view along line 6—6 of Fig. 2;

Fig. 7 is a view along line 7—7 of Fig. 3;

20 Fig. 8 is a perspective exploded view of the barrel assembly;

Fig. 9 is a schematic view showing the relationship of the bolt assembly and decelerator when the bolt assembly is in recoil position and the bolt is in full extended position in the carrier;

25 Fig. 10 is a view similar to Fig. 9 but showing the relationships of the follower with the cam slot and the bayonet lugs on the bolt with the helical cam surfaces in the decelerator during counterrecoil stroke of the bolt assembly when the bolt is in the locked extended position; and

30 Fig. 11 is a view similar to Figs. 9 and 10 but showing the relationships of the follower and cam slot and the bayonet lugs on the bolt with the helical surfaces in the decelerator when the bolt has been actuated thereby to battery position.

35 Shown in the figures is a firearm 12 provided with a cylindrical receiver 14 in which there is slidably mounted a bolt assembly 16 which is reciprocable between a recoil position and a battery position responsive to forces produced by the discharge of cartridges in the firearm. Bolt assembly 16 is of two-piece type and includes a nonrotatable carrier 18, which is energized for such reciprocation by conventional gas actuated means (not shown), and a bolt 20 telescopically mounted therein.

40 Provided in carrier 18 is a cam slot 22 which slidably engages a follower 24 on bolt 20 for rotating the bolt in a clockwise direction to a locked battery position when telescoped into the carrier and in a counterclockwise direction to an unlocked battery position when bolt 20 extends from carrier 18. Bolt 20 is releasably locked against telescoping and against rotary displacement relative to carrier 18 by a transversely actuated lock 26, as hereinafter described.

45 Mounted to the front end of receiver 14 is a barrel assembly 28 which includes a barrel 30, a barrel extension 32 and a decelerator 34. Barrel 30 is provided at the breech end with an external threaded portion 36 of reduced diameter which is terminated forwardly by a shoulder 38. Decelerator 34, which is cylindrical in configuration coaxially abuts the rear end of the barrel. Decelerator 34 is secured against rotation relative to barrel 30 by the engagement of a pair of lugs 40 extending longitudinally from the front end of the decelerator 34 with a pair of mating recesses 42 in the rear end of the barrel. Barrel 30, with decelerator 34 engaged therewith, is threadably mounted to the front end of barrel extension 32 so that the front end thereof contacts shoulder 38. Decelerator 34 is received by a mating bore 44

50 provided axially in barrel extension 32 and is thereby positioned in axial alignment with barrel 30 while an annular shoulder 46 terminating the rear end of such bore

contacts the rear end of the decelerator to maintain such decelerator in abutment with the rear end of barrel 30 and thereby secured against longitudinal displacement. Barrel extension 32 is fixedly mounted within the front end of receiver 14 by cooperating bayonet lugs 45 and a screw 47 extends radially through the receiver and barrel extension into barrel 30 to secure barrel assembly 28 against longitudinal and rotary displacement in the receiver.

Provided on the front end of bolt 20 is a head portion 48 which is extendable through suitable openings in barrel extension 32 and decelerator 34 to chamber a cartridge in barrel 30 and close the breech end thereof when the bolt is in the battery position. Extending radially from head portion 48 are a plurality of diametrically disposed pairs of bayonet lugs 50 which are longitudinally spaced thereon and which are rotatable alternately between mating pairs of bayonet lugs 52 in barrel extension 32, when bolt 20 goes into battery position, for releasably securing the bolt against longitudinal displacement in the lock position. The bayonet lugs 50 are positioned when bolt 20 is in the unlocked battery position to pass longitudinally through the bayonet lugs 52.

The front pair of the bayonet lugs 50 are engageable with cam surfaces 54, which are formed by a pair of diametrically disposed recesses 56 extending forwardly from the rear end of decelerator 34, just before bolt 20 reaches battery position. The cam surfaces 54 extend helically forward and in a clockwise direction from the rear end of decelerator 34 so that bolt 20 is spun helically in a forward and clockwise direction to gradually decelerate the forward movement thereof by converting the longitudinal movement thereof to helical movement. The left wall of cam slot 22 is curved outwardly, rearwardly from the front end thereof, to form a pocket 58 which receives follower 24 during counterrecoil movement of bolt assembly 16, as hereinafter described, and thereby provides for the helical displacement of follower 24 when bolt 20 is helically spun by the engagement of the bayonet lugs 50 with the cam surfaces 54.

The corners of the bayonet lugs 50 which engage the cam surfaces 54 are provided with radii, as noted at 60, to form a cylindrical surface for contact with the cam surfaces 54 and so broaden the impact area of bolt 20 with barrel assembly 28 and increase the sliding relationship therebetween. The front corners of the lugs 52, around which the bayonet lugs 50 are moved, are chamfered, as noted at 62, to provide clearances for the passage of the bayonet lugs 50.

The cam surfaces 54 are disposed so that the bayonet lugs 50 are delivered thereby directly between the bayonet lugs 52, as is best shown in Fig. 4, for a uniform transition from the helical displacement of bolt 20 by the cam surfaces to the subsequent rotary displacement of the bayonet lugs 50. The rotary displacement of bolt 20 is effected by the cooperation of the sliding engagement of the bayonet lugs 50 and 52 and the engagement of follower 24 in cam slot 22.

Lock 26, which releasably prevents bolt 20 from telescoping, is slidably disposed for transversal movement through carrier 18 adjacent the rear end of the bolt when adjacent the extended position thereof in the carrier. Lock 26 is slidably received by a segmental recess 64 formed in the top, rear end of bolt 20 by a laterally disposed chordal portion 66 which extends forwardly from the rear end of the bolt and which is terminated forwardly by a vertically disposed face portion 68. Lock 26 is provided with a segmental relief cut 70 which extends upwardly from the underside of the lock and which is disposed so as to unblock bolt 20 for retraction within carrier 18 when the lock is in the unlock position. When lock 26 is in the locked position relief cut 70 is misaligned with bolt 20 which therefore is blocked against telescoping into carrier 18 and the bottom side of the lock is in engagement with a chordal portion 66 so as to

prevent clockwise rotation of the bolt. Lock 26 is actuated to the unlock position, during the counterrecoil movement of bolt assembly 16, by the engagement of the end thereof with a cam 72 (Fig. 3) in the right side of receiver 14 and to the lock position, during recoil movement, by a cam 74 in the left side of the receiver. The cams 72 and 74 are disposed so as to actuate lock 26 between the lock and unlock positions thereof when the front bayonet lugs 50 are immediately rearward of engagement with the cam surfaces 54.

Thus, when bolt 20 is in locked battery position, where-in the bayonet lugs 50 and 52 are in engagement, and a cartridge is discharged in barrel 30, carrier 18 is energized for cyclic reciprocation in receiver 14. During the recoil stroke of carrier 18, cam slot 22 is moved along follower 24 and thereby rotates bolt 20 to the unlock position. As cam slot 22 is developed to rotate bolt 20 counterclockwise to the unlocking position, it is the right wall of the cam slot which slidably engages follower 24 to rotate bolt 20 during the recoil stroke of carrier. Follower 24 is directed by such right wall of cam slot 22 to the front portion thereof, forwardly of pocket 58 and thereby the bolt is correctly positioned for the engagement of chordal portion 66 with the underside of lock 26 and for the passage of the bayonet lugs 50 past the bayonet lugs 52. When follower 24 contacts the front end of cam slot 22, bolt 20 is picked up thereby to travel with carrier 18 to recoil position. Immediately after the pickup of bolt 20 by carrier 18 lock 26 is actuated to the lock position and thereby the bolt is releasably blocked against telescoping into the carrier and against rotary displacement. A dwell period is provided between the full extended position of bolt 20 in carrier 18, as shown in Fig. 9, and the position wherein the bolt is in engagement with lock 26 during counterrecoil stroke of the carrier, as shown in Fig. 10. This dwell period is such that when bolt 20 is in engagement with lock 26, follower 24 is positioned in pocket 58 and thereby free to be helically actuatable when the bolt engages decelerator 34.

As bolt 20 approaches battery position towards the end of such counterrecoil stroke lock 26 is actuated to the unlock position thereof so as to free the bolt for longitudinal and rotary movement relative to carrier 18 immediately before the front pair of the bayonet lugs 50 engage the cam surfaces 54 in decelerator 34. As has been explained hereinbefore, when the front pair of bayonet lugs 50 engage the cam surfaces 54 follower 24 is positioned in pocket 58 so that bolt 20 is free to be helically spun and the longitudinal movement thereof converted to helical movement for gradual deceleration. And has also been explained, cam surfaces 54 are so related to the bayonet lugs 52 that the bayonet lugs 50 are led directly by the cam surfaces into engagement with the bayonet lugs 52 so that the helical movement of bolt 20 is uniformly translated through the cooperation of cam slot 22 with follower 24 to rotary movement as carrier 18 continues forwardly relative to the bolt.

It is readily seen that when lock 26 is in the unlock position and follower 24 is being rotated across cam slot 22 from pocket 58, bolt 20 is virtually free of the mass of carrier 18 when the bolt contacts barrel assembly 28, to reduce the impact of bolt assembly 16 therewith, and the mass of the carrier is gradually united with the mass of the bolt because of the inclination of the cam slot and the frictional engagement of the bayonet lugs 50 with the bayonet lugs 52 which come into engagement when the follower reengages the cam slot.

Whereby, it is readily seen, bolt 20 is gradually decelerated through the device of this invention and that the impact of bolt assembly 16 with barrel assembly 28 is reduced so that little, if any, adverse effect is produced to affect the accuracy of firearm 12.

Moreover, when decelerator 34 becomes worn or mutilated from usage, it is easily replaced by removing barrel

assembly 28 from receiver 14 and then unscrewing barrel 30 from barrel extension 32 which frees the decelerator for removal and replacement so that firearm 12 is easily repaired without having to replace any major components.

Although a particular embodiment of the invention has been described in detail herein, it is evident that many variations may be devised within the spirit and scope thereof and the following claim is intended to include such variations.

I claim:

In a firearm including a receiver, the combination of a barrel assembly provided with a decelerator replaceably assembled to the breech thereof, a telescopic bolt assembly slidingly disposed in the receiver for reciprocation to and from a battery position, said bolt assembly including a carrier and a bolt telescopically disposed therein, a cam slot disposed in said carrier for cooperation with a follower in said bolt for rotating said bolt to and from a lock position during longitudinal movement of said carrier relative thereto, cam means disposed on said decelerator for engagement by said bolt when adjacent the battery position to convert the longi-

15 tudinal movement of said bolt assembly to helical movement of said bolt, a pocket portion extending from said cam slot and disposed therein to provide clearance for helical movement of said follower when said bolt is helically actuated by the engagement thereof with said decelerator, lock means for immovably connecting said carrier to said bolt to prevent the telescoping thereof into said carrier, and cam means in the receiver for actuating said lock means to disconnect said carrier from said bolt

20 and thereby release the mass of said carrier from that of said bolt when said follower is actuated into said clearance portion.
